ARTIFICIAL BAIT

William C. Klenk, III, Grosse Pointe, Mich.

Application May 21, 1951, Serial No. 15,264

Term of patent 14 years

(Cl. D31—4)

To all whom it may concern:

Be it known that I, William C. Klenk, III, a citizen of the United States, residing at Grosse Pointe, in the county of Wayne and State of Michigan, have invented a new, original, and ornamental Design for Artificial Bait, of which the following is a specification, reference being had to the accompanying drawing, forming part thereof.

Figure 1 is a side elevational view of an artificial bait embodying my new design.

Figure 2 is a top plan view thereof.

Figure 3 is a front end view thereof.

The dominant features of my design reside in those portions shown in full lines.

I claim:

The ornamental design for an artificial bait, substantially as shown and described.

WILLIAM C. KLENK, III.
